Application March 8, 1945, Serial No. 118,336

Term of patent 14 years

(Cl. D86—10)

To all whom it may concern:

Be it known that we, Robert L. Holland and Walter F. Nessen, citizens of the United States, residing at Chicago, in the county of Cook and State of Illinois, have invented a new, original, and ornamental Design for a Toilet Kit or the Like, of which the following is a specification, reference being had to the accompanying drawings, forming a part thereof.

In the drawings:

Figure 1 is a perspective view of a toilet kit or the like in closed position, showing our new design. The opposite end and side are similar to the end and side shown.

Figure 2 is a perspective view of the upper member of the kit,

Figure 3 is a perspective view of the tray and containers forming part of the kit, and

Figure 4 is a perspective view of the bottom member of the kit.

We claim:

The ornamental design for a toilet kit or the like, substantially as shown and described.

ROBERT L. HOLLAND.
WALTER F. NESSEN.
